CLAIM

The ornamental design for arm crutch padding, as shown and described.

DESCRIPTION

FIG. 1 is a front elevational view of the arm crutch padding showing my new design;

FIG. 2 is a rear elevational view thereof;

FIG. 3 is a left side elevational view thereof;

FIG. 4 is a right elevational view thereof;

FIG. 5 is a top plan view thereof;

FIG. 6 is a bottom plan view thereof; and,

FIG. 7 is a perspective view, shown in a position of use. The broken line showing of environment being for illustrative purposes only, and forms no part of the claimed design.
